US0D1079010S

(12) **United States Design Patent** (10) **Patent No.:** **US D1,079,010 S**
(45) **Date of Patent:** **** Jun. 10, 2025**

(54) **SPHYGMOMANOMETER**

(71) Applicant: **SHENZHEN JAMR TECHNOLOGY CO., LTD**, Shenzhen (CN)

(72) Inventor: **Liming Wang**, Shenzhen (CN)

(73) Assignee: **SHENZHEN JAMR TECHNOLOGY CO., LTD.**, Shenzhen (CN)

(**) Term: **15 Years**

(21) Appl. No.: **29/851,196**

(22) Filed: **Aug. 26, 2022**

(51) LOC (15) Cl. **24-02**

(52) U.S. Cl. **USPC D24/165**

(58) **Field of Classification Search**

USPC D24/165, 107, 134, 166, 167, 169, 168, D24/185, 186, 190, 231; D10/30, 38, 70, D10/78, 81, 125; D13/108, 168; D14/204, 214–216, 345, 487

CPC A61B 5/00; A61B 5/021; A61B 5/02141; A61B 5/02158; A61B 8/04

CLAIM

The ornamental design for a sphygmomanometer as shown and described.

DESCRIPTION

FIG. 1 is a perspective view of a sphygmomanometer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 2. The dash-dash broken lines in the drawings depict portions of the sphygmomanometer that form no part of the claimed design. The dot-dash broken lines represent the boundary of the enlarged portion and form no part of the claimed design.

1 Claim, 9 Drawing Sheets
